(57) CLAIM

We claim the ornamental design for a bottle, as shown and described.

DESCRIPTION

FIG. 1 is a top, front, left side perspective view of the claimed design;

FIG. 2 is a front elevation view of the claimed design of FIG. 1;

FIG. 3 is a rear elevation view of the claimed design of FIG. 1;

FIG. 4 is a left-side elevation view of the claimed design of FIG. 1;

FIG. 5 is a right-side elevation view of the claimed design of FIG. 1;

FIG. 6 is a top plan view of the claimed design of FIG. 1; FIG. 7 is a bottom plan view of the claimed design of FIG. 1; and,

FIG. 8 is a top, rear, right side perspective view of the claimed design of FIG. 1.

The evenly-dashed broken lines in the drawings illustrate the portions of the bottle that form no part of the claim. The dot-dash broken lines in the drawings define the bounds of the claim and form no part thereof.
